BED TRAY WITH ILLUMINATING MEANS

Webster E. Janssen, Bronxville, N. Y.

Application April 26, 1947, Serial No. 744,124

1 Claim. (Cl. 240—4)

1

The present invention relates to an improved table, bed tray or similar device provided with lighting means for reading or other purposes.

Objects and advantages of the invention will be set forth in part hereinafter and in part will be obvious herefrom, or may be learned by practice with the invention, the same being realized and attained by means of the instrumentalities and combinations pointed out in the appended claim.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a cross-sectional view of a typical and illustrative embodiment of the present invention said view being taken along line 1—1 of Fig. 3;

Fig. 2 is a perspective view of the lighting unit for the tray shown in Fig. 1;

Fig. 3 is a top plan view of the bed tray shown in Fig. 1;

Fig. 4 is a cross-sectional view taken along line 4—4 of Fig. 3;

Fig. 5 is a detail cross-sectional view taken along line 5—5 of Fig. 3;

Fig. 6 is a fragmentary cross-sectional view of a modified embodiment of the invention showing in detail the light mounting and reflector;

Fig. 7 is a front elevation of the embodiment of the invention shown in Fig. 6 with the removable reflector panel unit removed and wiring broken away;

Fig. 8 is a cross-sectional view taken along line 8—8 of Fig. 7;

Fig. 9 is a cross-sectional view taken along line 9—9 of Fig. 7; and,

Fig. 10 is a perspective view of the removable reflector panel unit for the embodiment shown in Fig. 6.

An object of the present invention is the provision of an improved bed tray or similar device for use by invalids or others wishing to eat and read in bed the tray including pivotal means for supporting the matter to be read and means for adequately lighting the reading matter. Another object of the invention is to provide such tray with lighting means which will fully illuminate the tray and reading matter but will not shine in the eyes of the person using the tray.

Referring now in detail to the illustrative em-

2

bodiment of the invention shown by way of example in the accompanying drawings, the tray is generally of a conventional form in so far as it is provided with a horizontal fixed panel 10, a pivotal panel 11 at the back of the tray, and front and rear legs 12 and 13 capable of being folded into the under side of the tray. As shown, the framework of the tray includes a pair of frame members 14 extending from the front to the rear of the tray upon which the stationary horizontal panel 10 is supported. Side panels 15 are provided secured to frame members 14 and extend somewhat above the panel 10 to form a ledge at either side thereof, and a rear panel 16 joins the rear ends of members 14 and likewise extends upwardly to form a rear ledge for the table portion of the tray.

As clearly shown in Fig. 1 of the drawings, the panel 11 is pivotally connected to the rear edge of the panel 10 by means of a pair of hinges 17, so that it may form a horizontal extension of the panel 10 at the rear of the tray or may be raised to provide a support for reading matter or other articles conveniently rested against it.

A prop member 18 with feet 19 is connected to a bar 20 on the back of panel 11 by means of hinges 21, and the feet are adapted to be seated in any of a plurality of notches 22 provided in the upper surfaces of frame members 14 toward the rear ends thereof. The panel 11 may thus be propped up and retained at the desired inclination with respect to the front stationary panel 10.

A pair of blocks 23 are secured to frame members 14 and front panel 10, and a second pair of blocks 24 are arranged at the rear of the tray secured to members 14 and rear panel 16, these blocks serving as supports for the folding legs 12 and 13. The pairs of legs 12 and 13 at either side of the tray are mounted on shafts 25 and smaller shafts 26 and 27 extending into apertures in blocks 23 and 24 respectively mount the legs for folding. Coiled springs 28 are arranged about shafts 26 biasing the leg and shaft assemblies 12, 13 and 25 toward the rear of the tray, and the legs 13 and their respective blocks 24 are provided with corresponding square extensions and depressions 29 and 30 respectively so that the legs may be secured in upright position and unlocked by displacing toward the front of the tray.

The lighting means for the bed tray of the present invention is incorporated in a unit which is easily assembled with the other parts of the tray or separated therefrom. The unit is shown in Fig. 2 of the drawings, and comprises a bottom horizontal panel 35 and a vertical panel 36

55

secured thereto. A pair of brackets 37 are mounted on panel 35 constituting holders and contacts for a fluorescent tube 38 removably positioned therein. Also mounted on the panel 35 are the usual ballast 39 and switch 40, the latter having its push button extending downwardly through the panel where it can be conveniently reached, and the former being connected to an electric power source by wiring 41.

Reflecting means are provided in connection with the light source described and, as embodied, comprise the reflector 42 shaped as shown to curve about the lower cylindrical surface of the lamp 38 and then has a substantially vertical reach 43 ending in a flange 44 which is secured to panel 35. At its other extent the reflector 42 is formed in a vertically extending portion 50 which bears against and parallels front panel 36, and a turned edge 45 is preferably provided fitted into a groove in the panel to anchor the reflector in place.

As shown in Figs. 1 and 3, the illuminating unit described may form the front portion of the bed tray, the panels 35 and 36 being the width of the tray, and the unit is secured in place by screws 46 extending through the front panel 36 into the ends of frame members 14, and screws 47 extending through lower panel 35 and into the bottom of the frame members. The horizontal panel 10 of the tray is formed with a rectangular relieved place at its front edge corresponding in length to the length of the fluorescent lamp 38, and a piece of glass or other translucent material 48 is positioned in the relieved place to allow illumination of the tray and likewise act as a portion of the horizontal table thereof. As shown in detail in Fig. 5 of the drawings, a pair of channel members 51 are preferably secured to the horizontal panel 10 one at either lateral margin of the rectangular relieved place to securely 40 and removably position the glass 48.

In the construction for a bed tray as shown and described it will be apparent that light from the lamp will be reflected and focused upwardly by the reflector 42 and the reach 50 thereof will reflect the light toward the back of the tray and directly upon the panel 11 when it is in a raised position. The tray and particularly the panel 11 are thus adequately illuminated, the light source is conveniently out of the way beneath the table of the tray, and the eyes of the user are protected from light glare by the front panel 36, which prevents any direct beam of light to the eyes.

Referring now to the modified embodiment of the invention shown in Figs. 6 to 10 inclusive of the drawings, the tray structure is generally similar to that of the embodiment already described except that a differently formed and positioned reflector is utilized and the lighting means is differently positioned. As shown, the tray is formed with a horizontal panel 52, it being understood that a tiltable back panel is associated therewith in the manner already described for the first embodiment of the invention. Forward blocks 53 are provided for mounting the front legs 54, and in this embodiment a lower transverse panel 55 extends between the side panels 56 and abuts the front surfaces of the blocks 53, being firmly secured in place in the tray structure.

The fluorescent light 57 is removably secured in a pair of contact brackets 58 which are secured to transverse panel 55 as shown in detail in Fig. 6. The reflector 59 of this embodiment of the

invention is secured to the vertical panel 60 of the removable unit 60-61, brackets 62 being utilized to strengthen the construction of the panel unit. The reflector 59 is provided with an upper extent 63 which is inclined to the vertical beginning at about the level of horizontal panel 52, and a wedge shaped backing member 64 may be used to brace the reflector. As in the previous embodiment described, a glass or other translucent member 65 is provided in a relieved place along a central portion of the front edge of panel 52. A suitable switch 66 is provided in a side panel 56, and a prong electric plug 67 is positioned at the other side of the tray, secured to panel 55, and extending through a suitable aperture in a panel 56. A suitable and conventional inductance may be provided in the lighting circuit.

In the embodiment of the invention just described it will be apparent that the reflector 59 will receive light from the light source 57 through glass panel 65 and reflect it toward the back of the tray and the inclined panel. The inclined extent 63 of the reflector serves to focus the light at the back of the tray, serving to distribute light over the back of the tray and the inclined back panel thereof. The removable panel unit 60-61 makes the fluorescent light, its wiring, switch, and connections conveniently accessible for repair or replacement.

It will be apparent that the device of the present invention is not limited in its usefulness to a bed tray, but may be utilized as a tray or table of general usefulness as, for instance, a make-up tray to hold cosmetics, and otherwise.

The invention, in its broader aspects, is not limited to the specific mechanisms shown and described but departures may be made therefrom, within the scope of the accompanying claim, without departing from the principles of the invention and without sacrificing its chief advantages.

What I claim is:

45 A bed tray of the character described comprising, in combination, a horizontal panel, a second panel forming an extension of said horizontal panel at the rear edge thereof pivotally interconnected to said horizontal panel to be positioned in the same plane as said horizontal panel or lifted to a raised position inclined with respect thereto, an elongated cylindrical fluorescent light, means for mounting said light beneath the level of said horizontal panel in front of the front edge thereof crosswise of the tray, said light extending a major proportion of the width of the tray, a vertical panel spaced from the front edge of the horizontal panel extending substantially above and substantially below said horizontal panel and being at least as wide as the length of said fluorescent light, a reflector curved about the entire lower half-circumference of the cylindrical surface of said light and extending substantially vertically upward along the surface of said vertical panel facing said panels to a place substantially above the upper surface of said horizontal panel, said reflector extending crosswise of the tray at least the full length of said light, and a translucent panel horizontally arranged at the front edge of said horizontal panel to form a horizontal extension thereof, said translucent panel being positioned above said light and at least as long as said light and extending to said vertical panel, whereby light is directed to said second panel when in raised in-

5

clined position by the portion of said reflector above the upper surface of the horizontal panel.

WEBSTER E. JANSSEN.
